Strong & Moody.
Hulling Mach.

Patented Aug 29, 1832.

Theodore F. Strong & Marcus T. Moody
Inventors Patent

The schedule referred to in the Letters Patent and
making part of the same containing a description in
the words of the said Theodore F. Strong & Marcus T. Moody
themselves of their improvement in the machine for
bullying, cleaning & polishing Barley, Rice &c called
"Strong & Moody's bulley, smutter & polisher."

To all persons to whom these presents shall come
Theodore F. Strong, House Carpenter & Joiner & Marcus T. Moody
Cabinet-Maker, both of Northampton in the County of
Hampshire and Commonwealth of Massachusetts send greet-
ings. We do know that we the said Theodore F. Strong
& Marcus T. Moody have jointly invented constructed made
and applied to ride a new and useful improvement in
the mode of bullying, cleansing & polishing of Barley, Rice,
Broom-corn & other small seeds, having a hard fibrous &
difficult to separate from the hull or husk called Strong
& Moody's bulley, smutter & polisher specified in the words
following to wit. This improvement consists of two
flat or short cylinders of any required diameter placed in
a perpendicular shaft similar to the stones in a quist
mill. The upper cylinder is made of cast iron having
a sheathing on the under side made of wood. The under
cylinder is made of wood & is firmly applied to a platform
The under side of the upper cylinder and the upper side
of the lower one are to be studded clothed or charged with
strong carb teeth, pins or points of metallet wire set in
leather or any other strong & elastic substance. The up-
per cylinder is moved by an upright shaft to which it
is applied, while the lower one is supported on a plat-
form connected with the quadrangular frame of the ap-
pliance.

supports the machinery, & iron or border of metal or wood is placed on the outer edge of the lower cylinder having an opening on one side thru which the seeds pass after having been run thru the cylinder. From the opening in the rim aforesaid the seeds are carried by a trough to a winnower & screen affixed to a small upright shaft within the quadrangular frame & after being winnowed & passed thru the screen the seeds are carried by a trough into another pair of cylinders made precisely like the first mentioned pair excepting the materials which are used for clothing studding or charging which are to be of a finer quality than the pair first mentioned. From this second pair of cylinders the seeds are to be passed thru a winnower & screen similar to those first above mentioned. When it is desired to give a better polish to the seeds than is produced by passing it thru the two pairs of cylinders above mentioned another pair of cylinders are to be added made precisely like those above mentioned except the clothing charging or studding which is to be made of dog-fish skin or of strong bristles or hair. The seeds are to be passed from thence into a winnower & from thence into a bolt covered with screen wire. Method of operation. The seed to be cleaned, sorted or polished is to be placed in a hopper leading into the first pair of cylinders from thence it passes into the first mentioned winnower & screen from thence into the second pair of cylinders from thence into the second winnower & screen from thence into the third pair of cylinders, from thence into the last mentioned winnower & from thence into the bolt. The said Hardy & Strong claim as their joint invention in the improvement herein specified & described the method of hulling, cleaning, polishing & winnowing of Rye, Barley, Wheat, Corn, Maize & other small seeds having a hard, brittle, &

difficult to separate from the hull or bustle, by means of a combination of flat cylinders in a perpendicular shaft clothed, charged or studded with said teeth pins or points of metal
the wire set in strong leather or any other strong elastic substance, & also for flat cylinders clothed charged or studded with bustle hair, or dog fish skin for burnishers of bustles herein specified and described. Be testimony that the above is a true specification of our said improvement as above described We have hereunto set our hands at Southampton aforesaid. This thirtieth day of July in the year of our Lord one thousand eight hundred and thirty two
